SUCTION CLEANER AND BAG ASSEMBLY
THEREFOR

Frederick Riebel, Jr., and Dewey M. Dow, Toledo,
Ohio, assignors to Air-Way Electric Appliance
Corporation, Toledo, Ohio, a corporation of
Delaware

Application August 26, 1931, Serial No. 559,476

9 Claims. (Cl. 183—51)

This invention relates to suction cleaners and particularly to the type employing a filtering bag assembly including a destructible porous paper dust collecting receptacle and a confining bag 5 of fabric or the like supporting and enclosing said paper receptacle and demountably supported upon the cleaner.

The present application includes subject matter disclosed in co-pending applications as follows: Frederick Riebel, Jr., and Dewey M. Dow, Serial No. 538,638, filed May 20, 1931, now Patent #1,905,059, of Apr. 25, 1933; Frederick Riebel, Jr., and Dewey M. Dow, Serial No. 549,492, filed July 8, 1931, now Patent #1,936,366 of Nov. 21, 1933; 15 Frederick Riebel, Jr., and Dewey M. Dow, Serial No. 549,491, filed July 8, 1931; and Frederick Riebel, Jr., Serial No. 549,627, filed July 9, 1931, now Patent #1,884,871 of Oct. 25, 1932.

An object of the present invention is to provide 20 a suction cleaner including a cleaner bag which is so constructed and mounted on the cleaner that one side of the bag may be folded downwardly while the bag remains supported from the cleaner by means of the other side thereof, 25 thus providing an opening in the side of the bag of considerable dimensions to allow easy removal and insertion of the destructible porous paper dust receptacle.

Another object of this invention is to provide 30 a suction cleaner including a cleaner bag, together with novel means for supporting the bag from the cleaner for quick and easy removal.

A further object is to provide such a cleaner and bag assembly in which the detachable supporting connection between the bag and cleaner is such as to allow either the entire removal of the bag from the cleaner or the detachment of one side for providing a side opening in the bag as hereinbefore mentioned.

40 A further object of this invention is to provide a suction cleaner including a fan casing and a removable handle provided with a nipple for detachable connection with the fan case, said nipple serving also as one portion of the means for supporting the bag.

Another object is to provide a suction cleaner including a switch casing, and a bag supporting member associated with said switch casing.

More specifically, it is our object to provide, in 50 a suction cleaner having a switch casing depending below the handle thereof, a latch element slidably mounted on the switch casing and adapted to receive a projecting element on the bag.

55 A further object is to provide a novel bag

structure for enclosing a paper dust collecting receptacle, including a pair of side walls having upper portions which are detached from each other both at the upper edges and the ends, and a flap extending between the side walls from the upper edge of one of them.

With these and other objects in view our invention consists in the combination construction and arrangement of the various parts thereof, whereby the objects contemplated are attained, as more fully set forth in the accompanying specifications, pointed out in our claims, and illustrated in the accompanying drawing, in which:

Fig. 1 is a side elevation of a cleaner embodying our invention, the cleaner bag being shown partly open. 15

Fig. 2 is a detail longitudinal sectional view through the bag supporting means and associated cleaner parts. 20

Fig. 3 is a detail sectional view taken transversely through the cleaner handle as indicated by the section line 3—3 of Fig. 2.

Fig. 4 is a transverse sectional view through the cleaner bag. 25

Fig. 5 is a detail sectional view through the lower portion of the switch casing and associated latch structure, as indicated by the line 5—5 of Fig. 2.

Fig. 6 is a plan view of the cap which co-acts with the switch casing to support the latch devices. 30

Fig. 7 is a rear elevation of the lower portion of the switch casing and associated latch structure. 35

Fig. 8 is a detail perspective view of a bag securing clip.

In the accompanying drawing, referring specifically to Fig. 1, we have used the reference character 10 to indicate the motor of the specific type of suction cleaner with which this invention deals. The motor 10 is surmounted by the fan casing 11, with one end of which the floor tool 12 communicates and the other end of which is provided with a neck 13 to receive the nipple 14 45 of the hollow suction handle 15.

The nipple 14, is shown in section in Fig. 2 and comprises the sleeve portion 16 which is pressed on the end of the hollow fibre handle 15 and the reduced end 17, which is received within the neck 13 and clamped by means of a set screw 18, co-acting with the ears 19 defining a slot in the split side of the neck 13. 50

The nipple 14 is provided with a pair of lugs 20 which are spaced apart as shown in Fig. 3 to 55

provide between them a slot 21, and the lower ends of which abut against the flat face 22 of the fan casing discharge neck 23, thus preventing rotation of the handle relative to the fan casing.

The slot 21, closed by the face 22, of the discharge neck 23, forms an opening through which the motor cord 24 is passed. The cord is thus securely held against sagging, and can only be released by removing the handle from the fan casing.

The switch casing 25, includes a ring 26, by means of which it is mounted upon the handle 15, and current is carried to the switch within 15 the casing 25 by means of an extension cord 27. From the switch the current is delivered through a plug and socket connection 28 to the motor cord 24.

The confining bag is formed of a sheet of fabric bent back upon itself to form the side walls 29, the upper edges of which are looped and sewed to provide the sleeves 30 through which are extended the supporting rods 31.

The bag securing clips 32, shown in Fig. 8, engage between them and the end portions of the rods 31 the material of the sleeves 30. The clips are provided with end walls 33 apertured as at 34 to receive the threaded shanks 35 of studs 36, which serve as means for attachment of the bag supporting devices which will now be described.

The lugs 20 of the nipple 14 are provided with recesses 37 to receive the studs 36 on the lower ends of the bag supporting rods 31.

The studs 36 on the upper ends of the bag supporting rods are secured by slidable latch devices 33.

These latch devices are preferably formed of strip metal, each being bent upwardly at one end to provide the keeper 39 apertured as at 40 (Fig. 5) to receive the stud 36.

The rear end of each latch device is bent downwardly as at 41 to provide a trigger, the portion 42 of which may be engaged by the finger of the operator.

The latch device 38 is slidably mounted against the lower face of the switch casing 25, and is held in position by a cap 43 the end walls 44 of which are recessed as at 45 to receive the intermediate or shaft portions of the latch devices.

Screws 46 extending through openings 47 in the cap 43, and threaded into bosses 48 in the bottom wall of the switch casing 25, secure the cap 43 in engagement with the switch casing. The central portions of the end walls 44 of the cap 43, defined between the slots 45, are extended upwardly beyond the level of the edges of the side walls 49 to provide the projecting portions 50 which are received in notches 51 formed in the end caps 52 and 53 respectively of the switch casing. These end caps thus serve the double purpose of supporting the rubber strain relief member 54 of the extension cord 27 and the insulating core members 55 of the plug connection 28, and also of securing the cap 43 against rotation.

A teat 56 is struck from the intermediate region of each latch shaft 38 and a teat 57 is struck upwardly from the bottom wall of the cap 43. The end loops of a coil spring 58 are received over the teats 56 and 57 respectively, the teats extending sufficiently across the space within the cap 43 to prevent the spring becoming disengaged.

Explaining now the operation of the invention, it will readily be seen how the spring 58,

exerting a pull against the latch device 38, will yieldingly urge the keeper 39 against the shoulder 60 of the stud 36. The rod 31 will thus be held under compression, which will secure the stud 36 at the lower end of the rod in its recess 37.

Attention is directed particularly to the arrangement of the latch member 38 so that portions thereof extend behind the switch casing and latch cap assembly at both ends. During the development of the present invention, the trigger 41 at one time was allowed to normally rest in contact with the end wall of the cap 43. It was discovered that in some cases the fibre handle 15 would elongate under certain conditions 15 of moisture or other weather conditions, sufficiently to hold the keeper out of engagement with the bag rod stud, or to hold it at a sufficient distance so that the bag rod would not be securely supported.

In the present construction, the latch device may be said to have a floating mounting, wherein it may adjust itself to any irregularities in the normal distance between the switch casing and the nipple 14, and will at all times exert 25 tension against the bag rod. Sufficient retractile movement of the latch is allowed to disengage the keeper from its associated stud and all that is necessary in order to remove the bag is to grasp the trigger 41, pull it rearwardly and 30 allow the bag rod to drop to the position shown in Fig. 1. The lower stud may then quickly be disengaged by grasping the hanging wall of the bag and pulling upwardly slightly in a direction 35 parallel to the handle.

The bag is provided with a flap 61 secured near the upper edge of one side wall 29 and extending downwardly between the two side walls (Fig. 4). The paper receptacle 62 is received behind the flap 61, i. e., between said flap and 40 the side wall to which the flap is secured. When the bag is inflated by air from the fan of the cleaner, the flap 61 will be frictionally engaged between the wall of the receptacle and the wall of the bag, and will support the receptacle across 45 the space between the bag rods 31. It may be noted in this connection that the bag rods are disposed with a substantial space between them.

The side walls 29 of the bag are secured together from the lower corners indicated at "A" 50 to points somewhat above the center of the bag as indicated at "B", and from there to the upper corners of the bag, are entirely detached as clearly shown in Figs. 1 and 4. Reinforcing tapes 63 are secured to the unattached edges of the 55 side walls, each tape extending from the corner of one side wall to the corresponding corner of the opposite wall.

The rods 31 support the upper edges of the bag against spreading under the pressure of air 60 delivered from the fan, and thus it is unnecessary to provide any means of connection between the upper edges of the bag.

It is found that the structure wherein the upper portion of one side wall of the bag may be 65 folded downwardly while the bag remains suspended from the other wall adds greatly to the convenience and utility of a cleaner of this type, since the paper receptacle may be very easily attached and detached with very little 70 likelihood of tearing the same while connection is being made to the discharge neck 23. In this connection it may be stated that it was formerly considered preferable to remove the bag entirely from the cleaner when changing paper 75

receptacles. The receptacle would first be enclosed within the bag and then the connection made between the receiving neck of the receptacle and the discharge neck of the fan casing. It is now found that the likelihood of tearing the paper is greatly diminished by attaching the receptacle while the bag remains suspended from the cleaner handle and the present invention wherein means are provided allowing the opening of the bag while it remains suspended, not only adds greatly to the convenience by eliminating the necessity of removing the bag entirely, but also reduces the likelihood of injury to the receptacle.

We claim as our invention:

1. In a suction cleaner having a fan casing discharge connection, a cleaner bag comprising opposed side walls one of which is individually supported from the cleaner at its upper edge, and the other of which has an upper portion detached, from the first mentioned side wall both at its upper edge and along its end edges from the upper corners of the bag to points intermediate said upper corners and the lower corners thereof, and downwardly foldable to provide a side opening in the bag, and means for detachably securing said foldable portion at its upper edge in bag closing relationship with the other side wall, said means being releasable while the bag remains suspended on the cleaner, said connection extending between the forward edges of the bag, and a flap extending downwardly from the upper extremity of one of said side walls, and received between the two side walls.

2. In a vacuum cleaner, a dust collecting bag including sleeves formed at its marginal edges, defining between them a mouth, rods extended through said sleeves and having projecting portions at their ends, and complementary devices on the cleaner releasably engaged with said projecting portions and supporting the bag.

3. In a vacuum cleaner, a dust collecting bag including a sleeve formed at its marginal edge, a rod extended through said sleeve, shouldered studs threaded into the ends of said rod and retaining it in the sleeve, and complementary devices on the cleaner, releasably engaged with said studs.

4. In a vacuum cleaner, a dust collecting bag, a rigid element longitudinally secured to the upper margin thereof, projections on the ends of said element, and complementary devices on the cleaner releasably engaged with said projections and supporting the bag.

5. A vacuum cleaner bag formed with a margin

nal sleeve, a rod extended through said sleeve, and including projecting end portions, and clips including U shaped portions embracing the sleeves and perforated end portions receiving said projecting rod end portions.

6. In a vacuum cleaner including spaced projecting parts, a latch slidably mounted on one of said parts and projecting therefrom at each end, a keeper on one end of the latch, a dust collector, projections on the dust collector engaged with the other projecting part and said keeper, and a trigger on the other end of the latch, both trigger and keeper being spaced from the projecting part in which the latch is mounted, and resilient means maintaining the latch in engagement with the bag projection.

7. In a suction cleaner including a handle and a projecting part near its lower end, a longitudinally rigid dust collector the lower end of which has an axially releasable, interfitting engagement with said projecting part, and a latch releasably engaging the dust collector near its upper end, and serving to hold the collector against axial movement, whereby to retain the lower end in engagement with the projecting part.

8. In a suction cleaner including a handle and projecting parts spaced longitudinally thereof, a longitudinally rigid dust collector provided at its ends with projecting elements one of which is detachably associated with one of said projecting parts, and a latch member slidably mounted on said other projecting part, spring urged in a direction toward the collector and parallel to the handle, and detachably engaged with the other projecting element, the length of the latch member, the length of the dust collector, and the distance between the projecting parts being so correlated that the engaging end of the latch member will be freely movable either toward or from its related projecting part when the parts are all in assembled relation.

9. In a suction cleaner including a handle, a fan casing exhaust connection and a projecting part adjacent said connection, a longitudinally rigid dust collector provided at its respective ends with projecting elements one of which is detachably associated with said projecting part, and a latch carried by the handle and releasably engaging the other of said elements, and serving to retain said projecting part adjacent said connection and the coacting projecting element in mutual engagement.
